UNITED STATES PATENT OFFICE.

MARGARET RUSSELL BENNETT AND HARRY RUSSELL, OF GARY, INDIANA.

HYGIENIC WATER RECEPTACLE.

Application filed May 26, 1924. Serial No. 716,077.

To all whom it may concern:

Be it known that we, MARGARET RUSSELL BENNETT and HARRY RUSSELL, citizens of the United States, residing at Gary, in the county of Lake and State of Indiana, have invented certain new and useful Improvements in a Hygienic Water Receptacle, of which the following is a specification.

This invention relates to new and useful improvements in hygienic water receptacles and has for its principal object to provide a receptacle such as a drinking glass or a pitcher wherein the same is provided with an ice compartment for keeping the water cold without causing the ice to come in contact with the drinking water.

One of the important objects of the present invention is to provide a receptacle of the above mentioned character, wherein the same is of such a construction as to enable the ice compartment to be readily and easily filled with ice, a suitable stopper being provided for the filling opening of the ice compartment to prevent any leakage from the ice compartment passing through the opening.

A further object of the invention is to provide a receptacle of the above mentioned character, wherein the same is of such a construction as to have the lower portion of the drinking compartment submerged in the ice compartment.

A further object is to provide a receptacle of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of a water pitcher with our invention associated therewith.

Figure 2 is a side elevation of a drinking glass showing the stopper for the ice compartment in front elevation, and

Figure 3 is a vertical section taken approximately on line 3—3 of Figure 2.

In the drawing wherein for the purpose of illustration is shown the preferred embodiment of our invention, the numeral 1 designates a water pitcher which is of the

well known construction and may be formed of any desirable material preferably glass and the same is provided with the usual pouring spout 2, and the handle 3. Arranged in the pitcher is the substantially cup-shaped dividing wall 4 the upper edge of which is connected to the intermediate portion of the pitcher and at a point approximately adjacent the bottom of the spout 2 in the manner clearly shown in Figure 1.

The cup shaped dividing wall 4 is molded with the pitcher and the bottom of the cup shaped dividing wall terminates at a point adjacent the bottom of the pitcher in the manner also clearly shown in Figure 1. This construction provides an upper compartment 5 which forms a water compartment while the bottom of the pitcher around the cup shaped dividing wall 4 provides an ice compartment 6.

The ice compartment 6 extends around the lower portion of the water compartment and for the purpose of filling the ice compartment we provide the pitcher 1 with a suitable opening in the rear portion thereof and a stopper such as is shown at 7 is adapted to be received in said opening for keeping the same closed. A rubber gasket shown at 8 is carried by the stopper for cooperation with the opening provided in the rear intermediate portion of the pitcher whereby a water tight joint is provided so as to prevent any possibility of the water formed in the ice compartment by the melting of the ice from leaking therethrough.

In Figure 2 of the drawing a drinking glass such as illustrated at 9 is shown and the same is also provided with a substantially cup shaped dividing wall 10 which extends from the intermediate portion of the glass to a point adjacent the bottom of the same. The cup shaped dividing wall 10 provides an upper water compartment 11 and a lower ice compartment 12, the latter extending around the lower portion of the water compartment in the manner shown and as heretofore more fully described. The ice compartment 12 is also provided with an opening 13 for the reception of a stopper 14, similar to the stopper 7, and a rubber gasket 15 is associated with the stopper for cooperation with the opening 13 whereby a water tight joint is provided.

It will thus be seen from the foregoing description, that a receptacle has been pro-

vided wherein the water compartment is adapted to be submerged in the ice compartment so that the water will at all times be kept cold and in a sanitary condition preventing the contamination of the water which is usually caused by ice being placed in the water. In the present invention the ice does not come in contact with the water but extends completely around the bottom of the water compartment in the manner as is obvious from the construction and description above set forth.

While we have shown the preferred embodiment of our invention, it is to be understood that various changes in the size, shape and arrangement of parts may be resorted to without departing from the spirit of the invention and the scope of the appended claim.

Having thus described the invention, what we claim is:—

A receptacle open at its top, a substan-

tially cup-shaped dividing wall disposed transversely in the receptacle, with its upper edges engaged against the intermediate portion of the receptacle and having the bottom thereof spaced from the bottom of the receptacle, said cup-shaped dividing wall providing an upper water compartment and a lower ice compartment at the open top of the receptacle a spout extended therefrom, said receptacle provided with an opening located below the upper edge of the cup-shaped dividing wall, and a handle mounted upon the receptacle and having its intermediate portion disposed opposite the opening, said opening being disposed on a side of the receptacle opposite to that on which is disposed the spout.

In testimony whereof we affix our signatures.

MARGARET RUSSELL BENNETT.
HARRY RUSSELL.
